(57) CLAIM

The ornamental design for two-piece cape garment, as shown and described.

DESCRIPTION

FIG. 1 is an isometric illustration showing the rear, upper and right side portions of the two-piece cape garment of my new ornamental design, as being worn;

FIG. 2 is a top view showing the two-piece cape garment of my new ornamental design;

FIG. 3 is a bottom view of the two-piece cape garment of my new ornamental design;

FIG. 4 is a front elevation view showing the two-piece cape garment of my new ornamental design, the rear elevation view being a mirror image of the front elevation view shown in FIG. 4; and,
